DESIGN FOR A HANDKERCHIEF

Vincent Fazio, Brooklyn, N. Y.

Application April 28, 1938, Serial No. 76,796

Term of patent 7 years

To all whom it may concern:

Be it known that I, Vincent Fazio, a citizen of the United States, residing in Brooklyn, in the county of Kings and State of New York, have invented a new, original, and ornamental Design for a Handkerchief, of which the following is a specification, reference being had to the drawing, forming a part thereof.

The figure of the drawing is a plan view of a handkerchief showing my design having an arrangement of flags of many nations with flags of the United States in each of the four corners.

I claim:

The ornamental design for a handkerchief, substantially as shown and described.

VINCENT FAZIO.
